PYRAZOLONE MONOAZO DYESTUFFS

Werner Kuster, Basel, Switzerland, assignor to
 J. R. Geigy A. G., Basel, Switzerland, a Swiss
 firm

No Drawing. Application December 3, 1951,
 Serial No. 259,695

Claims priority, application Switzerland
 December 12, 1950

6 Claims. (Cl. 260—163)

1

The present invention is concerned with a process for the production of chromable monoazo dyestuffs which are characterised particularly by their suitability for dyeing keratin fibres according to the single bath chroming method and so produce fast bluish-red dyeings.

The single bath chroming method, also known as the chromate or methachrome method, is very much favoured by the wool dyeing industry because of its simple working method and because it enables the dyer to form a direct judgement of the colour developed on the goods and so simplifies shading. By no means all chrome dyestuffs have the properties necessary for a good single bath chrome dyestuff: sufficient water solubility, stability to the chromic acid salts in the dyebath and above all, a good affinity to the fibre even in a neutral to weakly acid dyebath.

It has now been found that on coupling by the usual methods diazotised 6-nitro-4-alkyl or -4-cycloalkyl-2-aminophenols with 1-phenyl-5-pyrazolone-3-carboxylic acid-3'-sulphonic acid diamides, 1-(4'-chlorophenyl)-5-pyrazolone-3-carboxylic acid-3'-sulphonic acid diamides or 1-(6'-chlorophenyl)-5-pyrazolone-3-carboxylic acid-3'-sulphonic acid diamides, monoazo dyestuffs of the general formula:

are obtained wherein R represents a saturated hydrocarbon radical with from 4 to 8 carbon atoms and R' and R'' represent hydrogen or a lower alkyl or lower hydroxyalkyl radical, one X represents chlorine or hydrogen and the other X represents hydrogen. These monoazo dyestuffs produce full and fast bluish-red wool dyeings by the single bath chroming process without any additional acid within the usual dyeing time and with complete exhaustion of the dyebaths. Such dyestuffs are of particular value technically because they allow the wool component in staple fibres to be fast dyed while the cellulose component is protected to the greatest possible extent.

The diazo components usable according to the invention should have a saturated hydrocarbon

2

radical of from 4 to 8 carbon atoms in the 4-position which can either have a straight or branched chain or can be alicyclic, 6-nitro-4-tert, amyl-2-aminophenol is an advantageous diazo component. The coupling components usable according to the invention are obtained by condensation according to the usual methods from 3-hydrazinobenzene- or -3-hydrazinochlorobenzene-1-sulphonic acid amides and oxalacetic acid esters to produce 1-(3'-sulphonic acid amidophenyl)- or chlorophenyl)-5-pyrazolone-3-carboxylic acid esters which are then converted into the corresponding 3-carboxylic acid amides by reacting them with ammonia or lower primary aliphatic amines. The 3-hydrazinobenzene-1-sulphonic acid amides are produced from the corresponding amino compounds and may have a lower alkyl or lower hydroxyalkyl radical, for example a methyl, ethyl, hydroxyethyl group, at the nitrogen atom of the sulphonamide group. A variation of the method to produce the monoazo dyestuffs according to the invention, for which protection is also claimed, is that in many cases it is possible to couple the diazo components with 1-(3'-sulphonic acid amidophenyl)- or chlorophenyl)-5-pyrazolone-3-carboxylic acid alkyl esters and then to convert the 3-carboxylic acid ester groups in the dyestuff formed into 3-carboxylic acid amide groups by means of ammonia or lower primary aliphatic amines.

Suitable coupling components for this variation or for the direct process are, for example: 1-(3'-sulphonic acid amidophenyl)- or chlorophenyl)-, 1-(3'-sulphonic acid-N-methylamidophenyl)- or chlorophenyl-, 1-(3'-sulphonic acid-N-ethylamidophenyl)- or chlorophenyl- and 1-(3'-sulphonic acid-N-hydroxyethylamidophenyl)- or chlorophenyl)-5-pyrazolone-3-carboxylic acid ethyl esters and the corresponding 3-carboxylic acid amides, -3-carboxylic acid-N-methyl-, -N-ethyl- and -N-hydroxyethylamides. It is advantageous that in the acid amide groups of the dyestuffs according to the present invention hydroxyalkyl groups should only occur once in one of the two amido groups.

The alkali salts of the dyestuffs according to the present invention are violet-brown powders which dissolve in water with a bluish-red and in conc. sulphuric acid with an orange colour. They can be used directly or, advantageously, mixed with buffer salts such as sodium pyrophosphate and dispersing and capillary active substances for the dyeing of wool according to the single bath chroming process.

Because of their better suitability in the single

bath chroming process, the dyestuffs according to the present invention are superior to the similar known dyestuffs having sulphonic acid or carboxyl groups as coupling components.

The following examples illustrate the invention without limiting it in any way. The temperatures are given in degrees centigrade and, where not otherwise stated, parts are given as parts by weight. The relationship of parts by weight to parts by volume is that of kilograms to litres.

Example 1

22.4 parts of 6-nitro-2-amino-4-tert. amylphenol and 4.1 parts of sodium hydroxide are dissolved in 200 parts of water. 6.9 parts of sodium nitrite in 35 parts of water are added and the mixture is added dropwise to 25 parts by volume of conc. hydrochloric acid and 100 parts of water at a temperature not exceeding 3°. In this way a suspension of the greenish-yellow diazo body is obtained. On completion of the diazotisation the acidity of the diazo suspension is rendered neutral to Congo red with sodium bicarbonate whereupon a solution of 28.5 parts of 1-phenylpyrazolone-3-carboxylic acid amide-3'-sulphonic acid amide (M. P. 220-222° on decomposition) and 8 parts of sodium hydroxide in 100 parts of water at 0-3° is added. The reaction mixture is made weakly phenol phthalein alkaline by the addition of 10 parts of 25% ammonia, after which the temperature is slowly raised from 3° to 20°. The coupling is completed after 20 hours. The dyestuff which precipitates and which corresponds to the formula:

is filtered off and dried. It is a dark violet powder which dissolves in water with a red-violet and in conc. sulphuric acid with a brown-orange colour. The product, with advantage mixed with 10% of its weight of sodium carbonate and 2% of a dispersing agent, dyes wool from an acid bath in a brown-orange shade which on after-chroming changes to blue-red. A beautiful strong bluish-red shade is obtained by the single bath chroming process without, or with only a very slight addition of acid. The bath is completely exhausted. The dyeings produced both by the after-chroming process as well as by the single bath chroming process have very good wet and light fastness properties.

Very similar dyestuffs which are also excellently suitable for the single bath chroming process, are obtained if, in the above example, the diazo component is replaced by 21.5 parts of 4-nitro-2-amino-4-tert. butylphenol or by 24 parts of 6-nitro-2-amino-4-cyclohexyl phenol or if the coupling component is replaced by 30 parts of 1-phenylpyrazolone-3-carboxylic acid methyl amide-3'-sulphonic acid amide or by 33 parts of 1-phenylpyrazolone-3-carboxylic acid ethanol amide-3'-sulphonic acid amide.

The pyrazolones mentioned above are obtained for example, by converting m-aminobenzene sulphonate acid amide (M. P. 142°) by known methods

into the corresponding hydrazin and condensing the hydrazin with sodium oxalacetic acid ethyl ester to produce 1-phenylpyrazolone-3-carboxylic acid ethyl ester-3'-sulphonic acid amide.

5 The 1-phenylpyrazolone-3-carboxylic acid ethyl ester-3'-sulphonic acid amide is then pasted with 5 times the amount of 25% aqueous ammonia or 25% aqueous methylamine or 25% aqueous monoethanolamine and either left standing for 2 to 4 days at 20° or heated in a pressure vessel at 80-100° for 10-15 hours. This causes the pyrazolone carboxylic acid ethyl esters to dissolve, the alcohol radical of the ester being split off and replaced by the corresponding amide radical. 1-phenylpyrazolone-3-carboxylic acid amide or methyl amide or monoethanol amide-3'-sulphonic acid amide is obtained according to the amine used.

Example 2

20 22.4 parts of 6-nitro-2-amino-4-tert. amylphenol are diazotised as described in Example 1. A solution of 31.5 parts of 1-phenylpyrazolone-3-carboxylic acid ethyl ester-3'-sulphonic acid amide in 100 parts of water at 0-3° and 8 parts of sodium hydroxide are added to the diazo suspension after it has been neutralised with sodium bicarbonate. After about 30 minutes the reaction mixture is made weakly phenol phthalein alkaline with ammonia and the temperature is then slowly raised from 3 to 20°. The coupling is completed after 20 hours. The dyestuff which precipitates is filtered off and washed with a 2½% salt solution. The dyestuff in the form of a damp filter cake is pasted in 25% aqueous ammonia and left to stand for 3-4 days. The paste is then diluted with common salt solution and filtered; the residue is dried and mixed with 10% of its weight of calcined soda and 2% of a dispersing agent.

40 The treatment with ammonia converts the 3-carboxylic acid ester group in the dyestuff also into the 3-carboxylic acid amide group which is recognisable by the considerably more bluish shade of the chromed dyeing on wool in comparison with an analogous dyeing obtained with the starting material.

45 The dyestuff treated with ammonia described in this example is identical with the product fully described in Example 1.

Example 3

50 The coupling product of Example 2 is heated at room temperature in a closed vessel for 3 days with 20-30% aqueous methylamine. This changes the 3-carboxylic acid ethyl ester group into the 3-carboxylic acid methylamide group and the product corresponds to the formula

55 Similar conversions can be brought about in the same way with ethylamine or monoethanolamine.

60 In each case dyestuffs are obtained which dye wool in strong bluish-red shades with good wet and light fastness properties and which are characterised by their particular suitability for use in the single bath chroming process.

5

Example 4

A solution of 6.9 parts of sodium nitrite in 35 parts of water is added to a solution of 23.6 parts of 6-nitro-2-amino-4-cyclohexylphenol and 4.1 parts of sodium hydroxide in 200 parts of water. This mixture is added dropwise at 0-3° to 25 parts by volume of conc. hydrochloric acid and 100 parts of water.

A greenish-yellow suspension of the diazo body is obtained. On completion of the diazotisation, the acidity of the diazo suspension is partly neutralised with a little sodium bicarbonate and made neutral to Congo red whereupon a solution of 31 parts of 1-phenylpyrazolone-3-carboxylic acid methylamide-3'-sulphonic acid methylamide and 8.1 parts of sodium hydroxide in 200 parts of water at 0° is added. The mixture is made weakly phenolphthalein alkaline by the dropwise addition of 10 parts of 20% ammonia, after which the temperature is slowly raised to 20°. The diazonium compound has reacted after 20 hours. The dyestuff which precipitates and which corresponds to the formula

is filtered off, washed with 2½% salt solution and dried. It is a dark violet powder which dissolves in water with a red-violet and in conc. sulphuric acid with a brown-orange shade. It dyes wool, (with advantage mixed with 10% of its weight of sodium carbonate and 2% of a dispersing agent) an orange shade from an acid bath and on after-chroming produces a strong bluish-red colour. The great advantage of this product is that also in a single bath chroming process and both without or with only a very slight addition of acid, it dyes wool exactly the same shade from a completely exhausted bath.

Very similar dyestuffs are obtained if, in the above example the 23.6 parts of 6-nitro-2-amino-4-cyclohexylphenol are replaced by 22.4 parts of 6-nitro-2-amino-4-tert. amylphenol or 26.6 parts of 6-nitro-2-amino-4-octylphenol or if the 31 parts of 1-phenylpyrazolone-3-carboxylic acid methylamide-3'-sulphonic acid methylamide are replaced by 32.4 parts of 1-phenylpyrazolone-3-carboxylic acid methylamide-3'-sulphonic acid ethylamide or 36.8 parts of 1-phenylpyrazolone-3-carboxylic acid methylamide-3'-sulphonic acid monoethanolamide.

The pyrazolones mentioned above are obtained by starting from 3-aminobenzene sulphonemethylamide, -ethylamide or -monoethanolamide i. e. by condensation of the corresponding hydrazins with sodium oxalacetic acid esters to obtain the corresponding 1-phenylpyrazolone-3-carboxylic acid ester-3'-sulphonic acid alkylamides which by finally treating with aqueous 25% methylamine are converted into the 3-carboxylic acid methylamides.

Example 5

21.0 parts of 6-nitro-2-amino-4-tert. butylphenol and 4.1 parts of sodium hydroxide are dissolved in 200 parts of water and, together

6

with a solution of 6.9 parts of sodium nitrite in 35 parts of water are added dropwise at 0-3° to 25 parts by volume of conc. hydrochloric acid and 100 parts of water. The diazo compound forms a yellow coloured suspension. On completion of the diazotisation, the acidity of the diazo suspension is made neutral to Congo red by the addition of a little sodium bicarbonate, after which a solution of 32.0 parts of 1-(2'-chlorophenyl)-5-pyrazolone-3-carboxylic acid amide-5'-sulphonic acid amide and 8.1 parts of sodium hydroxide in 100 parts of water is added at 0-3°. The reaction mixture is made weakly phenolphthalein alkaline by the addition of about 10 parts of 25% aqueous ammonia. The temperature is then allowed to rise slowly from 3 to 20° and the coupling is complete after 20 hours. The dyestuff which precipitates and which corresponds to the formula

is filtered off and dried. It is a dark violet-brown powder which dissolves in hot water with a bluish-red and in conc. sulphuric acid with a brownish-orange colour. It is advantageous to grind the dyestuff well with some sodium carbonate and a dispersing agent. It dyes wool a brownish-yellow shade from an acid bath which changes on after-chroming to a bluish-red colour. Dyeings of the same shade and strength properties are obtained according to the single bath chroming process with no, or only a slight, addition of acid. The bath is completely exhausted.

Very similar dyestuffs are obtained if, in the above example, the diazo component is replaced by 22.4 parts of 6-nitro-2-amino-4-tert. amylphenol or 23.6 parts of 6-nitro-2-amino-4-cyclohexylphenol or if the coupling component is replaced by 33.5 parts of 1-(2'-chlorophenyl)-5-pyrazolone-3-carboxylic acid methylamide-5'-sulphonic acid amide or by 35 parts of 1-(2'-chlorophenyl)-5-pyrazolone-3-carboxylic acid ethylamide-5'-sulphonic acid amide.

The pyrazolones mentioned above are obtained for example by converting 2-chloro-1-aminobenzene-5-sulphonic acid amide (M. P. 156-158°) by methods known per se into the corresponding hydrazin and condensing this with sodium oxalacetic acid ethyl ester to 1-(2'-chlorophenyl)-5-pyrazolone-3-carboxylic acid ester-5'-sulphonic acid amide. The 1-(2'-chlorophenyl)-5-pyrazolone-3-carboxylic acid ethyl ester-5'-sulphonic acid amide is then pasted in 5 times the amount of 25% aqueous ammonia or 25% aqueous methylamine or 25% aqueous ethylamine and left standing at 20° for 2-4 days or heated in a pressure vessel to 80-100° for 10-15 hours. This causes the corresponding pyrazolone carboxylic acid ethyl esters to dissolve, the alcohol radical of the ester being split off and replaced by the corresponding amide radical. In this way 1-(2'-chlorophenyl)-5-pyrazolone-3-carboxylic acid amide-, methylamide- or ethylamide-5'-

7 sulphonic acid amide is obtained according to the amine use.

Example 6

22.4 parts of 6-nitro-2-amino-4-tert. amyl-phenol and 4.1 parts of sodium hydroxide are dissolved in 200 parts of water, 6.9 parts of sodium nitrite in 35 parts of water are added and the mixture is added dropwise at a temperature not exceeding 3° to 35 parts by volume of conc. hydrochloric acid in 100 parts of water. A yellowish-green suspension of the diazo compound is obtained. On completion of the diazotisation, the acidity of the diazo suspension is neutralised with sodium bicarbonate until the reaction is neutral to Congo red whereupon a solution of 32.5 parts of 1-(4'-chlorophenyl)-5-pyrazolone-3-carboxylic acid amide-5'-sulphonic acid amide and 8 parts of sodium hydroxide in 100 parts of water is added at 0-3°. The reaction mixture is made phenolphthalein alkaline with 10 parts of 25% ammonia and then the temperature is raised slowly from 3 to 20°. The coupling is complete after 20 hours. The dyestuff which precipitates and which corresponds to the formula

is filtered off, washed with 2½% salt water and dried.

It is a dark violet powder which dissolves in hot water with a bluish-red and in conc. sulphuric acid with an orange-brown colour. It is advantageous to grind the dyestuff well with some sodium carbonate and a dispersing agent. It dyes wool a yellowish-brown shade from an acid bath which changes on after-chroming to a bluish-red colour. Dyeings of the same shade and strength which have very good wet and light fastness properties are obtained according to the single bath chroming process with no, or only a slight, addition of acid. The bath is completely exhausted.

Very similar dyestuffs are obtained if, in the above example, the diazo component is replaced by 21.0 parts of 6-nitro-2-amino-4-tert. butyl-phenol or by 26 parts of 6-nitro-2-amino-4-octyl-phenol or if the coupling component is replaced by 34 parts of 1-(4'-chlorophenyl)-5-pyrazolone-3-carboxylic acid amide-5'-sulphonic acid methylamide or by 35.5 parts of 1-(4'-chlorophenyl)-5-pyrazolone-3-carboxylic acid amide-5'-sulphonic acid ethylamide.

The pyrazolones mentioned above are obtained by converting 4-chloraniline-5-sulphonic acid amide, -methylamide or -ethylamide by methods known per se into the corresponding hydrazins and condensing these hydrazins with sodium oxalacetic acid ethyl ester to the corresponding 1-(4'-chlorophenyl)-5-pyrazolone-3-carboxylic acid ethyl ester-5'-sulphonic acid amide, -5'-sulphonic acid methylamide or -5'-sulphonic acid ethylamide. The pyrazolone-3-carboxylic

8 acid ethyl esters so obtained are then pasted with 5 times the amount of 25% ammonia and then are either left standing at 20° for 2-4 days or heated in a pressure vessel to 80-100° for 10-15 hours. This causes the corresponding pyrazolone-3-carboxylic acid ethyl esters to dissolve, the alcohol radical of the ester being split off and replaced by the corresponding amide radical. In this way 1-(4'-chlorophenyl)-5-pyrazolone-3-carboxylic acid amide-5'-sulphonic acid amide, -5'-sulphonic acid methylamide or -5'-sulphonic acid ethylamide is obtained.

Example 7

22.4 parts of 6-nitro-2-amino-4-tert. amyl-phenol and 4.1 parts of sodium hydroxide are dissolved in 200 parts of water, 6.9 parts of sodium nitrite in 35 parts of water are added and the mixture is added dropwise at a temperature not exceeding 3° to 35 parts by volume of conc. hydrochloric acid in 100 parts of water. A greenish-yellow suspension of the diazo compound is obtained. On completion of the diazotisation, the acidity of the diazo suspension is neutralised with sodium bicarbonate until the reaction is neutral to Congo red whereupon a solution of 35.5 parts of 1-(4'-chlorophenyl)-5-pyrazolone-3-carboxylic acid ethyl ester-5'-sulphonic acid amide and 8 parts of sodium hydroxide in 100 parts of water is added at 0-3°. The reaction mixture is made phenolphthalein alkaline with 10 parts of 25% ammonia and then the temperature is raised slowly from 3 to 20°. The coupling is complete after 20 hours. The dyestuff which precipitates is filtered off and washed with 2½% salt water. The dyestuff, in the form of a damp filter cake, is pasted with 25% aqueous ammonia and left to stand for 3-4 days at room temperature. It is then diluted with common salt solution, filtered, dried and ground with sodium carbonate and a substance having a dispersing action.

The treatment with ammonia converts the carboxylic acid ester group in the dyestuff also into the carboxylic acid amide group which is recognisable by the considerably more bluish shade of the chromed dyeing on wool in comparison with an analogous dyeing obtained with the starting materials.

The dyestuff treated with ammonia described in this example is identical with the product fully described in Example 6.

Very similar dyeings are obtained if the coupling product of 6-nitro-2-amino-4-tert. amyl-phenol and 1-(4'-chlorophenyl)-5-pyrazolone-3-carboxylic acid ethyl ester-5'-sulphonic acid amide is treated with about 25% aqueous solutions of methyl-ethyl- or hydroxy-ethylamine instead of with ammonia. In this way, dyestuffs are obtained which have a carboxylic acid methylamide, ethylamide or hydroxyethylamide group instead of the carboxylic acid ester group.

Example 8

0.2 part of the dyestuff obtained according to Example 1 is added to a solution of 1 part of dehydrated sodium sulphate, 0.2 part of sodium monochromate and 0.3 part of ammonium sulphate in 400 parts of water. 10 parts of wool are entered at 50°, the bath is brought to the boil within 1 hour and kept at the boil for 1 hour to fully develop the shade. The wool, which has been dyed a bluish-red shade, is rinsed and dried.

What I claim is:

1. A monoazo dyestuff having the general formula:

wherein R represents a saturated hydrocarbon radical with 4 to 8 carbon atoms, R' and R'' represent a member selected from the group, consisting of hydrogen, lower alkyl and lower hydroxylalkyl radicals and one X represents a member selected from the group consisting of hydrogen and chlorine, and the other X represents hydrogen.

2. A monoazo dyestuff having the formula:

3. A monoazo dyestuff having the formula:

4. A monazo dyestuff having the formula:

5. A monoazo dyestuff having the formula:

6. A monoazo dyestuff having the formula:

WERNER KUSTER.
